DISPENSING CONTAINER

William Taylor Bouchelle, Scarsdale, N. Y., assignor to The Lord Baltimore Press, Baltimore, Md., a corporation of Maryland

Application January 20, 1943, Serial No. 473,034

6 Claims. (Cl. 222—561)

The present invention relates generally to containers and more particularly to a dispensing container made of cardboard, paper and the like.

Dispensing containers are useful in connection with products which are used at intervals, for example, tooth powder, talcum powder, bath salts and numerous other items of a similar nature. It is generally desirable, although not always essential, that the containers retain the product without leakage during shipment and storage, and that they may be readily opened for use and readily closed when not in use. Such containers are sold in large quantities because of their extensive use; hence, improvements reducing their cost, facilitating their manufacture or increasing their utility are constantly sought by container manufacturers and users.

The present invention aims to provide an improved inexpensive container which may be used for storing, shipping and dispensing and which may be readily opened and closed during use. The improved container is completely closed during shipment and storage and hence minimizes the escape of dusty products. The improved dispensing means are inexpensive in construction and may be readily utilized for repeatedly opening and closing the package.

An object of the present invention is to provide an improved dispensing package.

Another object of the invention is to minimize the escape of dust from powdered material packed in a dispensing package.

Another object of the invention is to provide a simple and improved dispensing means.

Another object of the invention is to provide an improved dispensing container having an inner sealing container and an outer protecting container therefor.

Another object of the invention is to provide a combined inner and outer container having a dispensing outlet with the inner and outer containers adhered to each other adjacent to the outlet.

A further object of the invention is to provide a dispensing container formed from the usual types of cartons or boxes with minimum changes therein.

Other and further objects of the invention will be obvious upon an understanding of the illustrative embodiment about to be described or will be indicated in the appended claims, and various advantages not referred to herein will occur to one skilled in the art upon employment of the invention in practice.

A preferred embodiment of the invention has

been chosen for purposes of illustration and description and is shown in the accompanying drawing, forming a part of the specification, wherein

5 Fig. 1 is an exploded view illustrating the parts of the preferred embodiment prior to their assembly;

10 Fig. 2 is a fragmentary sectional view through the upper end of a sealed package showing the dispensing member in partly open position;

Fig. 3 is a sectional view transversely of the upper end of a sealed package showing a sifter top with a punch in position after perforation of the inner bag at one of the apertures;

15 Fig. 4 is a perspective view of the upper end of a package embodying a modified construction;

Fig. 5 is a fragmentary view similar to that illustrated in Fig. 4 showing the aperture closing member locked in its upper position;

20 Fig. 6 is an exploded view of another embodiment of the invention;

Fig. 7 is a sectional view of the upper end of the inner container shown in Fig. 6 taken along the line 7—7; and

25 Fig. 8 is a perspective view of the upper end of an inner container illustrating a circular score line in the end thereof adapted to facilitate the formation of an aperture in the inner container.

30 Referring again to the drawing and more particularly to Figs. 1 and 2 illustrating a preferred embodiment of the invention, there is shown an inner container 1 which may be of a more or less fragile nature and which is adapted to form

35 a secure and substantially dust-proof seal about the contents of the package and an outer container 2 adapted to extend about the inner container to protect it. A slide member 4 fits in the upper end of the outer container 2 to cooperate with apertures in the end to provide dispensing means for the package.

The preferred form of the outer container 2 will be described in detail first with the understanding that various types of containers may

45 be utilized, and without any intention of limiting the invention to the precise details of construction or the materials preferred. The outer container 2 is illustrated herein as a cardboard container of the tuck-in type. The lower end 50 may have a pair of opposed end flaps 5 which fold down into a substantially horizontal position and a flap 6, which folds over the flaps 5 with a tuck-in portion 7 that extends down along the opposite side wall of the container to close the end. Suitable locking slits 8 may be formed

at the junction of the flap 6 with the tuck-in portion 7 so that it will engage the adjoining edges of the flaps 5 when tucked into the package to lock the flap 6 in closed position.

The upper end of the container is constructed to cooperate with the slide member 4 and is preferably formed with a short end flap 9 on one side and a long end flap 10 on the opposite side having a bent portion 11 at a side edge adapted to rest against the side of the container. The flap 10 may be folded into a substantially horizontal position to cover the end of the container and has an aperture 12 therein for dispensing purposes. A flap 14 extends from the side of the container and is adapted to be folded over the flap 10 with the tuck-in portion 15 passing between the bent portion 11 of the flap 10 and the side of the container to close the end of the container. An aperture 16 is formed in the flap 14 to register with the aperture 12 when the end is in closed position. A recess 17 is also provided at one end of the flap 14 to expose the tab or the end 21 of the slide member 4 for the operation thereof as will be described hereinafter.

The slide 4 in its preferred form may have a horizontal part 18 with an aperture 13 therein adapted to cooperate with the apertures 12 and 16 in the upper end of the package. The slide member preferably has a vertical portion 19 which terminates a substantial distance from one end as shown at the edge 20 thereof. The tab 21, forming an extension of the horizontal portion 18 has a slit 22 adapted to be engaged by the nail of the thumb or fingers for initiating the opening of the package. After the tab 21 is projected beyond the side of the package, the package may be opened and closed without the use of the slit 22.

The slide member 4 is inserted into the upper end of the package over the flap member 10 after the latter is moved to its closed position and prior to the closing of the outer flap 14. The vertical portion 19 of the slide member 4 extends down into the outer container 2 in sliding engagement with the inside thereof; the horizontal portion 18 fits on the upper side of the flap 10. After the slide member 4 is inserted as described, the flap member 14 is closed over both the slide member 4 and the flap 10 to close the package. The position of the parts in the closed package may be observed in the sectional view of the upper end of the package shown in Fig. 2. It will be noted that the slide member 4 is intermediate the flaps 10 and 14 of the outer container. It will also be noted that the vertical portion 19 of the member 4 is considerably shorter than the corresponding dimension of the outer container 2. In this way, the vertical portion 19 serves as a guide for the slide member 4 and at the same time, its edge 20 engages the side of the box to serve as a stop for limiting the opening movement of the slide member 4. A portion of the tab 21 of the member 4 is exposed by the recess 17 in the flap 14 so that it may be engaged for sliding the opening member 4 back and forth. A slit 22 may be utilized for moving the slide member where resistance to movement is encountered.

While the outer container has certain advantages and may be used alone for some types of products, the present invention contemplates the provision of an inner container 1 for securely sealing the contents within the outer container. While the inner container may be a box, a bag and also other types of containers, the preferred

embodiment illustrates a bag made of thin material, for example paper, parchment, "glassine," "cellophane," "pliofilm" and similar materials. Such materials are preferred as they are light and inexpensive and at the same time form a dust-proof seal. In the drawing, only the upper end of the bag is shown and both the upper and lower ends may be closed in the usual fashion, either by heat, by adhesive, by folding or by a combination of these. As illustrated in the preferred embodiment in Fig. 1, the bag is delivered by the bag manufacturer with one end closed by fold 24 adhered in position by a suitable adhesive or by heat. In assembling the inner and outer containers 1 and 2 and the side member 4, a suitable form (not shown) may be used over which the bag may be placed with its closed end extending upwardly. Thereafter, the outer container 2 may be placed over the bag 1 on the form and the upper end closed with the slide member 4 in place as described.

At the time the box 2 is placed over the bag 1 or prior to doing so, an adhesive 27 (Fig. 2) is applied on the inside of the flap 10 so that the closed end of the inner bag is firmly adhered to the top of the box. In view of the fact that the aperture 12 is already in the flap 10, glue will be omitted from the portion of the bag beneath the aperture. This tends to produce a more sanitary package by reason of the fact that the product does not contact the glue even after the package is opened. Any other suitable means may be utilized for adhering the closed end of the bag to the underside of the flap 10. The use of adhesive is an important element in the invention although it is not essential in all cases. Adhering the closed end of the bag firmly to the top of the outer box provides a unitary structure and permits the bag to be perforated to form a sifter top or to be cut out to form an aperture therein without difficulty. In addition the inner bag cannot separate from the box at the dispensing outlet and the product cannot lodge between the bag and the box during use. These are important advantages of the invention.

The combined containers may then be removed from the form after the assembly operation and delivered, with their open ends up, to a filling machine. Thereafter the open end of the bag 1 may be closed and sealed in any suitable manner and likewise the flaps 5 and 6 on the open end of the container 2 may be tucked in to close the package. Both the inner container 1 and the outer container 2 may be shipped folded so that they take up a minimum of space in shipment from the manufacturer to the packer. The latter may then assemble the containers as described above.

Upon purchasing the package, the consumer moves the slide 4 by means of the tab 21 to its fully open position. The slide is shown partially open in Fig. 2 and fully open in Fig. 3. In view of the fact that the bag 1 has no perforation in it, the package is sealed independently of the slide member 4. The apertures 12, 16 and 13, when in registry, expose a portion of the bag and the consumer may take a knife or other sharp instrument and cut a suitable aperture in the bag which will then register with the other apertures so that it may be opened and closed by movement of the slide member 4. The contents of the package may then be dispensed as desired.

The sectional view in Fig. 3 is transverse to that illustrated in Fig. 2 and illustrates the flap 10 formed with perforations 12'. These perfora-

rations likewise expose portions of the inner bag and a pointed instrument, such as a pin 26, may be utilized for perforating the bag adjoining the perforations 12. In order to improve the operation of the construction as explained above, a suitable adhesive 27 is preferably utilized for securing the flap 10 to the closed end of the bag 1.

Some packers prefer dispensing openings in the side of the container to minimize the contact between the dispensed product and the outside of the container. The present invention is shown applied to such a package in Figs. 4 and 5. In Fig. 4 a container 30 is shown with its upper end closed by flaps 31 in any suitable manner. A pair of apertures 32 are provided in one side of the container and a sliding collar 34 serves to open and close the apertures. The collar is shown in its lower position with its apertures open in Fig. 4 and is shown in its upper position with the apertures closed in Fig. 5. A suitable tongue 35 may be cut in the side of the package to engage over the lower edge of the collar 34 to lock it in closed position. Without some means of locking the collar in its upper position, the constant jarring during shipment might cause the collar to slide down to the lower end of the container, which would be objectionable. Where the collar is locked in position as shown in Fig. 5, it is held in place regardless of whether or not the cartons containing the packages are inverted during shipment and handling. The outer container 30 preferably has an inner bag-like container as illustrated in Fig. 1 adhered to the outer container in the area surrounding the dispensing opening in the outer container, which may be perforated by the consumer for dispensing the product. In operation, the collar 34 may be raised slightly and the tongue 35 pressed into the plane of the side of the container permitting the collar to slide over it to open and close the aperture 32.

Another embodiment of the invention is illustrated in the exploded view of Fig. 6. An outer container 40 may be closed from the side by end flaps 41 and side flaps 42. In Fig. 5 the flaps are shown closed at the right of the container and open at the left. The opposite sides of the container at one end are formed with a pair of slots 44 adapted to receive and retain diametric edges of a disc 45. The diameter of the disc 45 is slightly greater than the width of the box and hence may be flexed sufficiently to be inserted into the recesses 45 in setting up the box. The disc has an aperture 46 registering with an aperture 47 in the end of the box 40 to form a dispensing outlet. Preferably the disc has a peripheral projection 48 for limiting the rotary movement thereof by engagement with the respective sides of the box. The consumer in using the box may engage the edge of the disc 45 at the exposed portions extending through slots 44 to rotate it until the apertures 46 and 47 are in registry for dispensing the product and until they are out of registry for closing the package.

While the box described above has utility without an inner container, preferably an inner bag or box is utilized to provide a better seal. As illustrated in Fig. 6 the inner container 41 may be a tuck-in box of the usual type with a perforations 50 in one end thereof adapted to register with the recesses 47 in the outer box 40. Preferably the perforations 50 in the inner box are closed by a piece of paper, "glassine," or "cellophane" 51 adhered to a surface of the box by a suitable adhesive as shown at Fig. 7. It is to

be noted that the sectional view in Fig. 7 is through the inner box only and not through the completed package. The inner box is not described in detail as various types of boxes may be utilized. The inner box 49 seals the product and may be inserted into the outer box as shown in Fig. 6 and the flaps 41 closed to completely seal the package. The consumer opens the package by rotating the disc 45 until the aperture 46 therein registers with the aperture 47 in the outer box. At this point, the perforations 50 in the inner box are exposed. The consumer may then use a pin or other pointed instrument to perforate the sealing member 51 on the inside of the inner container after which the rotatable disc 45 may be utilized for opening and closing the container during the consumption of the contents.

In Fig. 8 the upper end of the inner box 49 is shown with a circular score 52 which registers with the aperture 47 in the outer box when inserted in the box 40. The consumer may use any suitable instrument for removing the disc 54 formed by the score lines 52.

25 The operation of the several embodiments will be clear from the respective descriptions and further elaboration would be repetitious.

It will be seen that the present invention provides a package which will form a secure seal for various products such as powders, crystals and the like. The seal prevents dusty products from escaping and minimizes deterioration of many products due to imperfect sealing. The construction is simple and easy to manufacture from readily obtainable materials. The inner and outer containers may be made with existing machinery requiring only minor adjustments therein. Likewise, the packages may be filled and closed by existing machinery thereby minimizing the investment required for utilizing the invention. The construction is rugged and fully capable of withstanding the rough usage to which it may be subjected.

45 As various changes may be made in the form, construction and arrangement of the parts herein without departing from the scope and spirit of the invention and without sacrificing any of its advantages, it is to be understood that all matter herein is to be interpreted as illustrative and not 50 in a limiting sense.

Having thus described my invention, I claim:

1. In a device of the class described, the combination of an inner container, an outer container having a plurality of flaps for closing an end thereof, two of said flaps having registering apertures therein to permit access to said inner container, an adhesive for adhering the portion of the inner container about the aperture to the inner apertured flap to facilitate perforating the inner container and to retain said perforation in alignment with said registering apertures and a member slidably mounted between said flaps for opening and closing said apertures.

2. In a device of the class described, the combination of a bag forming an inner container, an outer container of cardboard having two superimposed flaps for closing one end thereof, said superimposed flaps having registering apertures therein, an adhesive adhering the inner of said apertured flaps to said inner container to facilitate perforating the inner container and to retain said perforation in alignment with said registering apertures and a member slidably mounted between said superimposed flaps for opening and closing said registering apertures.

3. In a device of the class described, comprising the combination of a paper-like bag forming an inner container, an outer container of cardboard having two superimposed flaps for closing one end thereof, said superimposed flaps having registering apertures therein, said paper-like bag being adhered to the inner of said superimposed flaps to facilitate perforating the inner bag and to retain said perforation in alignment with said registering apertures, and a member slidably mounted between said superimposed flaps for opening and closing said registering apertures to permit perforation of said bag and dispensing of the contents through said apertures.

4. In a device of the class described, the combination of a bag made of flexible material forming an inner container, an outer container of cardboard having two superimposed flaps for closing one end thereof, said superimposed flaps having registering apertures therein, an adhesive adhering the inner of said apertured flaps to said inner container about the aperture therein to facilitate perforating the bag and to retain said perforation in alignment with said registering apertures and a member slidably mounted between said superimposed flaps for opening and closing said registering apertures, the outer flap having a cut away portion at one end thereof to facilitate access to said slidable member for operating it to open and close the registering apertures.

5. In a device of the class described, the combination of an inner container, an outer con-

tainer having a plurality of flaps for closing an end thereof, two of said flaps having registering apertures therein to permit access to said inner container, an adhesive for adhering the portion 5 of the inner container to the inner apertured flap about the aperture therein and a slidable member having a portion extending between said flaps for opening and closing said apertures and having a second portion substantially at right 10 angles to said first portion adapted to fit between said inner and outer containers and serve as a guide therefor and also as a means for limiting the longitudinal movement of the slidable member in opening and closing the registering apertures.

6. In a device of the class described, the combination of an inner container, an outer container having a plurality of flaps for closing an end thereof, two of said flaps having registering 20 apertures therein to permit access to said inner container, an adhesive for adhering a portion of the inner container to the inner apertured flap, said inner apertured flap having a portion at right angles thereto, adapted to extend downwardly into the container and rest between the inner and outer container and a slidable member mounted between said flaps for opening and closing said apertures, said slidable member having a portion at right angles thereto adapted to 25 extend between the sides of said inner and outer containers and to serve as a stop limiting the longitudinal movement thereof.

WILLIAM TAYLOR BOUCHELLE.
